[57] CLAIM

I claim the ornamental design for a noise maker, as shown and described.

DESCRIPTION

FIG. 1 is a perspective view of a noise maker showing my new design;

FIG. 2 is a side elevational view thereof, the opposite side being identical;

FIG. 3 is a side elevational view thereof, in an alternate position;

FIG. 4 is a top plan view of FIG. 1, the bottom being identical; and,

FIG. 5 is an end elevational view, the opposite end being identical.
